UNITED STATES PATENT OFFICE.

CHARLES E. JONES, OF SCHENECTADY, NEW YORK, ASSIGNOR TO GENERAL ELECTRIC COMPANY, A CORPORATION OF NEW YORK.

TREATMENT OF SMALL METAL-COATED PARTS.

Application filed October 13, 1926. Serial No. 141,395.

The present invention relates to improvements in the process of tinning or coating small metal parts of the type usually employed in the assembly of radio or like apparatus, and more particularly to a method of treating such small metal parts immediately after they have been taken out of a tinning or galvanizing bath. Heretofore in the tinning or galvanizing of small metal parts considerable difficulty has been encountered in removing excess metal from the parts and also in preventing the parts from sticking or fusing together. For example, in tinning small parts it has been customary to place them in a wire basket which is momentarily immersed in molten metal. After removing the basket from the molten metal the excess coating metal is removed by agitating or shaking the basket and the parts are then poured out on to an inclined wire screen which carries the coated parts into a cooling fluid, such as water, or the like. With this arrangement, considerable excess metal adheres to the coated material, and frequently the parts become fused together into a solid mass.

According to the present invention, after an excess portion of the coating metal has been removed, as in the old method, by shaking the basket container, the small metal parts, while still very hot, are poured through a hopper on to an inclined chute which may, if desired, be heated to an elevated temperature. An air pipe is fitted into the upper end of the chute, and as the metal parts fall through the hopper and towards the bottom of the chute, they are subjected to an air blast at a pressure of about 80 pounds to the square inch. The air blast removes all excess metal, provides a smooth, bright coating, and effectively prevents the plated parts from adhering or fusing together.

The novel features which are characteristic of my invention will best be understood from reference to the following specification taken in connection with the accompanying drawing, in which Fig. 1 represents a view, partly in section and partly in elevation, of the apparatus whereby my invention may be carried into effect, while Fig. 2 is a perspective view of the air supply pipe which is fitted into the upper end of the chute.

Referring to the drawing, I have indicated at 1 a tank which may be partially filled with water or other cooling medium, and on which

an inclined chute 2 is supported. The chute 55 is substantially rectangular in cross section and is provided near the upper end thereof with a hopper 3, and a pipe 4 which extends across the entire width of the chute. The pipe 4 is perforated in a lengthwise direction, as indicated in Fig. 2, and is connected to a suitable source of air pressure through the pipes 5. A valve 6 is mounted in the air pipe and may be manually operated to control the supply of air to the 60 pipe 4. The lower end of chute 2 is provided with a wire mesh screen 7, which extends downwardly towards the tank 1. Screen 7 directs the material from chute 2 into a wire basket 8 which rests on the bottom of tank 1 and at the same time serves to relieve the air pressure in chute 2 and thereby prevent the water from being blown out of the tank.

In the operation of the device, the valve 6 is 75 opened and air pressure of about 80 pounds per square inch is directed into the chute. The tinned or metal coated parts are then poured while still at an elevated temperature, into the hopper 3. As the metal coated material falls from the hopper towards the bottom 80 of the chute, the air blast from pipe 4 is applied directly to the metal coated parts driving them towards the lower end of the chute and into the tank 1. The air blast applied in this manner prevents the small metal parts from adhering together and at the same time provides a smooth metal coating entirely free from excess metal.

For the successful operation of my method, it is essential that the metal coated material be poured into the hopper 3 before the metal has cooled appreciably, as otherwise it would be impossible to prevent fusion of the metal parts. I would find it advantageous, although not absolutely essential, to heat the chute during the operation of the process to a temperature in the neighborhood of 700° F. This may be done by means of an electric heating coil 10, or if desired, by other suitable means, as for example, a steam coil or a gas flame applied directly to the external part of the chute. Ordinarily either cold or hot air may be employed in the air blast, but it will be found preferable to use a heated air blast in order to assist in maintaining the coated metal at a high temperature during its passage through the chute.

What I claim as new and desire to secure by Letters Patent of the United States is:

1. The method of treating metal parts which have been coated by immersion in liquid metal, which comprises pouring the metal-coated parts, while still at an elevated temperature, into a chute and applying an air blast to the metal-coated parts at the upper end of such chute.
10. 2. The method of treating metal parts

which have been coated by immersion in liquid metal, which comprises pouring said coated parts while still at an elevated temperature onto a downwardly inclined surface and into the path of an air blast directed downwardly and substantially parallel to said surface.

In witness whereof, I have hereunto set my hand this 12th day of October, 1926.

CHARLES E. JONES.
